UNITED STATES PATENT OFFICE.

RUSSEL FRISBIE, OF CROMWELL, CONNECTICUT, ASSIGNOR TO THE J. AND E. STEVENS COMPANY, OF SAME PLACE.

DESIGN FOR TOY SAVINGS-BANK.

Specification forming part of Design No. **6,619**, dated April 29, 1873; application filed March 31, 1873

To all whom it may concern:

Be it known that I, RUSSEL FRISBIE, of Cromwell, in the county of Middlesex and State of Connecticut, have invented a Design for a Toy-Bank, of which the following is a specification:

The nature of my design is fully represented in the accompanying drawing, to which reference is made.

Figure 1 represents the front side of the bank. Fig. 2 represents the back, and Fig. 3 an end view of the same.

Upon the front is a representation of a door with an arched top containing the word "Bank," supported by plain side columns. There are two steps to this door. Upon the opposite side, or rear, there is an arched recess with one step of approach, as shown in the drawing. On this side, above the recess,

are two oval windows and an opening for receiving money, as shown in Fig. 2. On the corners and top of the front and back are dentated bands of the form shown. The ends are plain, except that the corners at the sides have dentated projecting bands like the front and rear. The roof projects beyond the sides of the building, and is plain, flat-sided, and hipped. On the top is a flat rectangular block surmounted by a cupola with its upper edge dentated like the corners of the building.

What I claim as my invention is—

A design for a toy savings-bank, substantially as above described.

RUSSEL FRISBIE.
